G. A. MOORE.

FLY SWATTER.

APPLICATION FILED MAR. 15, 1920.

Patented Oct. 5, 1920.

Inventor,

George A. Moore;

By

A. B. Leapham
Attorney.

UNITED STATES PATENT OFFICE.

GEORGE A. MOORE, OF MEDFORD, MASSACHUSETTS.

FLY-SWATTER.

1,354,775.

Specification of Letters Patent.

Patented Oct. 5, 1920.

Application filed March 15, 1920. Serial No. 366,051.

To all whom it may concern:

Be it known that I, GEORGE A. MOORE, a citizen of the United States, and a resident of Medford, in the county of Middlesex 5 and Commonwealth of Massachusetts, have invented certain new and useful Improvements in Fly-Swatters, of which the following is a full, clear, and exact specification.

10 The object of this invention is the construction of an improved device for killing flies, of the type known as a "fly swatter," which device shall be inexpensive to manufacture, durable, effective and incapable of 15 injuring polished surfaces upon which it may be struck.

To render the handle inexpensive, I construct it of wire, and to make it effective and non-injurious to furniture, the "swatting" portion is composed of felt, fabric, sheet rubber, or other yielding material, supplying it with a resiliency flexible frame by which it is connected with the handle.

25 The drawing forming part of this specification is a face view of the device.

The handle and frame of the device are composed of a single length of wire, the wire being bent over upon itself at substantially its midlength to compose the handle portion, the two sections 1 and 2 being suitably spaced, and twisted together at 3. Immediately beyond this juncture 3, the portion 2 is bent into a semicircle 4, and the portion 1 is continued as a diameter of the semicircle 4 and is then curved over away from the semicircle 4 to form a second semicircle 6 concentric with the other and of equal diameter. The portions of the 40 wire beyond the part 3 I prefer to designate as the frame for the support of the swatting portion.

This swatting member 7 I prefer to compose of comparatively thin felt cut in a circular form, although it may be of any suitable fabric, sheet rubber or other yielding and non-metallic material. This felt is preferably circular and of a larger diameter than the circle 4, 6, and is provided with a 50 circular row of holes 9 disposed in pairs,

the two holes in each pair being nearer together than are the pairs from each other.

In applying the swatting sheet to the frame, the wire semi-circles 4, 6 are 55 threaded through the holes 9 in the manner shown in the drawing, so that the wire chord 5 and the longer lengths of wire between the pairs of holes 9 are all above the top surface of the member 7. The space 60 between the two holes of a pair being much nearer together than the spaces between the pairs, the wire-portions beneath these short spaces will press upward the felt above to cause said wire-portions to be sufficiently 65 above the under surface of the felt member 7 to insure they cannot strike the surface of any hard object upon which the swatter descends.

Through the greater portion of the felt 70 member 7 are punched numerous holes 10 for the purpose of permitting the free passage of air, in order to reduce the current of air produced by the swatter as it swiftly descends upon a fly.

75 What I claim is:

1. A fly swatter comprising a sheet of fibrous material having perforations through certain parts thereof, a handle, and connection between said sheet and handle 80 consisting of a length of wire threaded back and forth through said perforations, the wire being of sufficient rigidity to press away from it each portion of the sheet lying between the two perforations penetrated by the corresponding portion of the wire.

2. A fly swatter comprising a sheet of fibrous material having two concentric but oppositely disposed semi-circles of perforations, a handle, and connection between the handle and sheet consisting of two concentric but oppositely disposed semi-circular wire portions, the same being disposed whereby a rotation of the sheet can cause 95 both said wire portions to be threaded through said perforations.

3. A fly swatter comprising a circular sheet of fibrous material having two concentric but oppositely disposed semi-circles 100 of perforations, said semi-circles being un-

equal in radius, and a length of wire bent over upon itself near its mid-length to compose a handle, the terminal portions of the wire being curved to form two oppositely disposed unequal semi-circles equal in radii to those of the semi-circles of perforations, said parts being so disposed that when the centers of the said semicircles are super-

posed, and the sheet rotated thereon, the ends of the wire portions can be threaded 10 through said perforations.

In testimony that I claim the foregoing invention, I have hereunto set my hand this 11th day of March, 1920.

GEORGE A. MOORE.
